Primary Examiner — Derrick E Holland

(74) Attorney, Agent, or Firm — Schmeiser, Olsen & Watts LLP

(57) **CLAIM**

The ornamental design for a wind turbine, as shown and described.

DESCRIPTION

FIG. 1 is a front elevation view of a wind turbine showing the new design;

FIG. 2 is a rear elevation view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a perspective view thereof;

FIG. 8 is a partial detailed view of FIG. 1;

FIG. 9 is a partial detailed view of FIG. 2;

FIG. 10 is a partial detailed view of FIG. 3;

FIG. 11 is a partial detailed view of FIG. 4;

FIG. 12 is a partial detailed view of FIG. 5;

FIG. 13 is a partial detailed view of FIG. 6; and,

FIG. 14 is a partial detailed view of FIG. 7.

(Continued)

The broken lines shown represent the portions of the wind turbine that form no part of the claimed design.

1 Claim, 14 Drawing Sheets
